COMBINED DOLL AND VEHICLE

Joyce C. Clark, San Pedro, Cyril Gordon Shireman, Rolling Hill Estates, David Weissmann, Palos Verdes, and John W. Gardner, Hermosa Beach, Calif., assignors to Mattel, Inc., a corporation of California

Filed Nov. 21, 1967, Ser. No. 9,484

Term of patent 14 years

(Cl. D34—15)

Fig. 1

Fig. 2

Fig. 3

The dominant features of our design reside in the full line portions shown.

We claim:

The ornamental design for a combined doll and vehicle, as shown and described.
